UNITED STATES PATENT OFFICE.

JAMES A. HENDLEY, OF MIDDLETON, CONNECTICUT, ASSIGNOR TO THE RUSSELL MANUFACTURING COMPANY, OF MIDDLETON, CONNECTICUT, A CORPORATION OF CONNECTICUT.

WOVEN FABRIC.

Application filed April 9, 1928. Serial No. 268,420.

The invention consists in a woven fabric embodying in novel combination and coordination, described herein and particularly pointed out in the claims at the close of the 5 description, features of fabric-construction by which are produced original and distinctive effects characterized by longitudinal bands of gathers and longitudinal ribs intervening between and alternating with said 10 bands. I have in view, more particularly, the production of a fabric which is elastic longitudinally, in virtue of the incorporation of elastic cords in the said longitudinal ribs, but the principles of the invention are applicable, also, in the production of fabric in which inelastic cords are embodied and the fabric consequently is non-elastic.

An illustrative embodiment of the invention in the shape of a fabric which is elastic 20 longitudinally in virtue of the employment of elastic cords is shown in the accompanying drawings, in which latter,—

Fig. 1 is a face view of a portion of the said elastic woven fabric comprising the said 25 embodiment, the fabric being shown in its normal contracted state.

Fig. 2 is a face view of the same, shown in an extended state.

Fig. 3 is a view on the order of a diagram, 30 illustrative of the fabric construction, with the fibrous threads and elastic cords separated from one another so as to render the relations of the threads and cords to one another more plainly apparent.

Having reference more particularly to Figs. 1 and 2,—Longitudinal bands of gathers such as aforesaid are represented at 1, 1, &c., and at 2, 2, &c., are shown longitudinal ribs such as aforesaid, intervening between and alternating with said bands of gathers, as mentioned. In Fig. 1 the gathers and the ribs are shown as they appear in the normal contracted state of an elastic fabric, and as they appear in the case of non-elastic fabric. Fig. 45 2 shows the appearance thereof in the extended state of an elastic fabric. The prominence of the ribs 2, 2, is due in part to the employment of the cords 3, 3, &c., as cores or stuffers within the said ribs.

The component elements of the fabric which is illustrated in the drawings are fibrous warp-threads 5, 5, (shown best in Fig. 3), fibrous weft 6, (Fig. 3), the cords 3, 3, which already have been mentioned, and

the leno stitching threads 4, 4, to which reference is made hereinafter. In the case of an elastic fabric the cords 3, 3, &c., are composed of rubber; in the case of an inelastic fabric they are composed of other suitable material. When the said cords are composed of rubber they preferably are gimped; that is to say, furnished with a wrapping or coating of fibrous threads, partly on account of portions of the cords being visible between the overlying floats of the leno stitching threads 4, 4, &c., particularly in the extended state of the fabric, (see Fig. 2), and partly for other practical reasons prevailing in the art. The wrapping or coating is colored appropriately to secure the desired effect in the 70 appearance of the fabric.

When a comparatively wide rib without undue thickness, or prominence in the fabric, is desired, each rib contains, as in the drawings, a pair of cords 3, 3, lying side by side. 75

Throughout the width of the fabric the fibrous warp-threads 5, 5, and the weft 6 are interwoven with each other to produce cloth-texture. As shown by Fig. 3, the cords 3, 3, &c., lie upon the face of the said cloth-texture, and are bound to the cloth-texture by means of the leno stitching threads 4, 4. Each of the said leno stitching threads is interwoven so that as shown in the diagram, Fig. 3, it is caught under a weft-pick at one side of the corresponding rubber cord, then passes diagonally over the top of such cord to the opposite side of the latter, then at the said opposite side of the cord is caught under an adjacent weft-pick, then passes diagonally 90 in the reverse direction over the top of the cord so that it returns to the first-mentioned side of the cord, where it is caught under a weft-pick, and so on. Thus, the leno stitching thread zig-zags back and forth across the top 95 of the rubber cord, and is caught by weft-picks at the opposite sides of the cord alternately.

The cloth-texture is of a construction providing less fulness longitudinally of the fabric at the cords 3, 3, &c., than in the bands 1, 1, &c., intermediate the cords. This result is secured in the present instance through a relationship between the weft-picks and the fibrous warp-threads immediately adjacent a 105 cord which permits the successive picks at the cord to occupy less space longitudinally of the fabric than in the general width of a band 1.

Thus, in the present instance, as illustrated by Fig. 3, whereas the fabric-texture of the general width of the respective bands 1, 1, &c., is of a plain or tabby weave in which each 5 weft-pick crosses over one warp-thread and under the next, and so on, the crossings of the next weft-pick being relatively reversed, the construction at the respective ribs is such that a weft-pick floats at one face of the fabric 10 relative to two warp-threads, in this instance the two warp-threads between which the cord is located (one warp-thread being at one side laterally of the cord and the other warp-thread being at the other side laterally of the 15 cord), while the next weft-pick floats at the opposite face of the fabric relative to such two warp-threads. Hence, at the cord the weft-picks are permitted to come together more closely, and to overlap with each other 20 more or less, so that in the beating-up of the weft-picks in the course of the weaving, and/or in the contraction of the cords in the case of an elastic fabric, the relative shortening of the fabric-texture at the cords causes 25 the fullness of the bands 1, 1 &c., to form into gathers such as those shown in Figs. 1 and 2. This shortening is promoted by the fact that the floats of the leno stitching thread engage 30 with weft-picks only at every second weft-pick, (first at one side of the cord with the weft-pick which is at the back of the said warp-threads, and then at the opposite side of the cord with the similarly located weft-pick,) leaving one weft-pick unbound by such 35 thread at each point where the latter floats diagonally altogether across the top of the cord, (see Fig. 3), and by the further fact that at either side of the cord the leno stitching thread engages with only one weft-pick in 40 every succeeding four.

It will be observed in Figs. 1 and 2 that the interlooping of the respective leno stitching threads with the weft-picks establishes a peculiar character in the case of the gathers. 45 As a general rule, the latter extend transversely of the respective bands 1, 1, &c., each gather extending from a point in connection with one cord at which a salient angle of the corresponding leno stitching thread engages 50 with a weft-pick, to a point at the next adjacent cord where a salient angle of the corresponding leno stitching thread engages with one of the neighboring weft-picks. This causes the gathers to form in a diagonal relationship with respect to the ribs, as shown 55 in Figs. 1 and 2, imparting a novel and characteristic effect to the general fabric.

The marginal band 7 in Fig. 3 constitutes 60 an edge-finish. The fabric-construction of such band is that of a twill, in which the weft-picks are capable of approaching more closely together than in the bands 1, 1, &c., so that in the completed fabric, and in the contracted state thereof in the case of an elastic fabric, 65 such band 7 is flat and without gathers. The

cord 31, gimped in case it is composed of rubber, around which the successive weft-picks are returned in extending back and forth across the fabric, provides for the production of a rounded bead-like edge-finish or 70 selvage.

In practice, color-effects are produced through employing leno stitching threads 4, 4, of such color or colors as may be deemed proper, contrasting or not with the color of 75 the general cloth-texture. I have in various instances employed threads 4, 4, &c., of different colors for the various longitudinal ribs of a piece of webbing. This difference in the colors of such threads is indicated in Fig. 3 80 by different shadings. The longitudinal lines of floats at the back of the fabric will show the color of weft 6. This may correspond with that of the general cloth-texture or may contrast therewith, &c., as deemed desirable. 85

Each cord lies upon the weft-floats aforesaid, and is bound in place thereon by the leno stitching thread 4. The said floats cover the back of the cord, and they combine with one another to form at the back of the fabric a rib-like effect. The gathers aforesaid are formed at the back of the fabric, as well as at the face of the latter, so that the fabric-back resembles closely the fabric-face in respect of being characterized by alternating longitudinal 95 bands of gathers and longitudinal ribs.

In the case of a fabric rendered elastic longitudinally through the employment of cords composed of rubber, a special function performed by the zig-zagging of the leno 100 stitching thread transversely across a cord, from one side of the latter to the other, is that of binding the rubber cord at the respective crossings so as to prevent the rubber from creeping lengthwise in the fabric. The creeping referred to is the well-known action which is liable to occur, away from the cut end of a piece of elastic webbing that has been sewed into a garment or the like.

What is claimed as the invention is:—

1. A woven fabric having longitudinal bands of gathers and longitudinal ribs intervening between and alternating with said bands of gathers, comprising:—fibrous warp-threads and weft interwoven in cloth-texture, 115 cords upon the surface of such cloth-texture at spaced intervals, and leno stitching threads by which said cords are bound to the cloth-texture, each of the leno stitching threads interwoven so that it is caught under a weft-pick at one side of the corresponding cord, then passes diagonally over the top of the cord and at the opposite side of the cord is caught under a subsequent weft-pick, and then passes diagonally in the reverse direction over 120 the top of the cord and at the first side of the cord is caught under a subsequent weft-pick, and so on, the said cloth-texture of a construction providing less longitudinal fulness of the cloth-texture longitudinally at the cords than 125

in the bands intermediate the cords, with resulting formation of the greater longitudinal fulness of the said intermediate bands into transversely-extending gathers.

- 5 2. An elastic woven fabric having longitudinal bands of gathers and longitudinal ribs intervening between and alternating with said bands of gathers, comprising:—fibrous warp-threads and weft interwoven in 10 cloth-texture, elastic cords upon the surface of such cloth-texture at spaced intervals, and leno stitching threads by which said elastic cords are bound to the cloth-texture, each of the leno stitching threads interwoven so that 15 it is caught under a weft-pick at one side of the corresponding elastic cord, then passes diagonally over the top of the elastic cord and at the opposite side of the elastic cord is caught under a subsequent weft-pick, and 20 then passes diagonally in the reverse direction over the top of the elastic cord and at the first side of the elastic cord is caught under a subsequent weft-pick, and so on, the 25 said cloth-texture of a construction providing less longitudinal fulness of the cloth-texture at the elastic cords than in the bands intermediate the elastic cords, with resulting formation of the greater longitudinal fulness of said intermediate bands into transversely-extending gathers.

3. A woven fabric having longitudinal bands of gathers, longitudinal ribs intervening between and alternating with said bands upon the fabric face, and longitudinal bands of weft-floats at the back corresponding in position with said ribs, comprising:—fibrous warp-threads and weft interwoven in cloth-texture, cords upon the surface of such cloth-texture at spaced intervals, with the said cloth-texture of a construction providing a line or series of weft-floats at the back of each cord, and further providing less longitudinal fulness at the cords than in the bands intermediate the cords with resulting formation 45 of the greater longitudinal fulness of the said intermediate bands into transversely-extending gathers, and leno stitching threads by which said cords are bound to the cloth-texture, each of the leno stitching threads 50 interwoven so that it is caught under a weft-pick at one side of the corresponding cord, then passes diagonally over the top of the cord and at the opposite side of the cord is caught under a subsequent weft-pick, and 55 then passes diagonally in the reverse direction over the top of the cord and at the first side of the cord is caught under a subsequent weft-pick, and so on.

4. An elastic woven fabric having longitudinal bands of gathers, longitudinal ribs intervening between and alternating with said bands upon the fabric face, and longitudinal bands of weft-floats at the back corresponding in position with said ribs, comprising:—fibrous warp-threads and weft

interwoven in cloth-texture, elastic cords upon the surface of such cloth-texture at spaced intervals, with the said cloth-texture of a construction providing a line or series of weft-floats at the back of each elastic cord, and further providing less fulness at the elastic cords than in the bands intermediate the elastic cords, with resulting throwing of the greater longitudinal fulness of the said bands into transversely-extending 70 gathers, and leno stitching threads by which said elastic cords are bound to the cloth-texture, each of the leno stitching threads interwoven so that it is caught under a weft-pick at one side of the corresponding elastic cord, then passes diagonally over the top of the elastic cord and at the opposite side of the elastic cord is caught under a subsequent weft-pick, and then passes diagonally in the reverse direction over the top of the elastic cord and at the first side of the elastic cord is caught under a subsequent weft-pick, and so on.

5. A woven fabric having longitudinal bands of gathers and longitudinal ribs intervening between and alternating with said bands, comprising:—fibrous warp-threads and weft-threads interwoven in cloth-texture, cords upon the surface of such cloth-texture at spaced intervals, with the cloth-texture construction at the respective cords characterized by one weft-pick being floated back of the cord, at the contiguous face of the cloth-texture, relative to warp-threads between which the cord is located, and the next weft-pick being floated at the opposite face of the cloth-texture relative to such warp-threads, whereby the cloth-texture forms less longitudinal fulness of material at a cord than in the band between two cords, with resulting formation of the greater longitudinal fulness of the said band into transversely-extending gathers, and leno stitching threads by which said cords are bound to the cloth-texture, each of the leno stitching threads interwoven so that it is caught under a weft-pick at one side of the corresponding cord, then passes diagonally over the top of the cord and at the opposite side of the cord is caught under a subsequent weft-pick, and then passes diagonally in the reverse direction over the top of the cord and at the first side of the cord is caught under a subsequent weft-pick, and so on.

6. An elastic woven fabric having longitudinal bands of gathers and longitudinal ribs intervening between and alternating with said bands, comprising:—fibrous warp-threads and weft-threads interwoven in cloth-texture, elastic cords upon the surface of such cloth-texture at spaced intervals, with the cloth-texture construction at the respective elastic cords characterized by one weft-pick being floated back of the elastic cord, at the contiguous face of the cloth-texture, relative

to warp-threads between which the elastic cord is located, and the next weft-pick being floated at the opposite face of the cloth-texture relative to such warp-threads, whereby the 5 cloth-texture forms less longitudinal fulness of material at an elastic cord than in the band between two elastic cords, with resulting throwing of the greater longitudinal fulness of the said band into transversely-extending 10 gathers, and leno stitching threads by which said elastic cords are bound to the cloth-texture, each of the leno stitching threads interwoven so that it is caught under a weft-pick at one side of the corresponding elastic cord, 15 then passes diagonally over the top of the elastic cord and at the opposite side of the elastic cord is caught under a subsequent weft-pick, and then passes diagonally in the reverse direction over the top of the elastic 20 cord and at the first side of the elastic cord is caught under a subsequent weft-pick, and so on.

7. A woven fabric having longitudinal bands of gathers and longitudinal ribs intervening between and alternating with said bands, comprising:—fibrous warp-threads and weft-threads interwoven in cloth-texture, cords upon the surface of such cloth-texture at spaced intervals, with the cloth- 25 texture construction at the respective cords characterized by one weft-pick being floated back of the cord, at the contiguous face of the cloth-texture, relative to warp-threads between which the cord is located, and the 30 next weft-pick being floated at the opposite face of the cloth-texture relative to such warp-threads, whereby the cloth-texture

forms less longitudinal fulness of material at a cord than in the band between two cords, with resulting formation of the 40 greater longitudinal fulness of the said band into transversely-extending gathers, and leno stitching threads, each of which zig-zags back and forth across the top of a cord and is caught at the opposite sides of the 45 cord alternately by weft-floats at the under face of the cloth-texture.

8. An elastic woven fabric having longitudinal bands of gathers and longitudinal ribs intervening between and alternating with said bands, comprising:—fibrous warp-threads and weft-threads interwoven in cloth-texture, elastic cords upon the surface of such cloth-texture at spaced intervals, with the cloth-texture construction at the 50 respective elastic cords characterized by one weft-pick being floated back of the elastic cord, at the contiguous face of the cloth-texture, relative to warp-threads between which the elastic cord is located, and the next weft- 55 pick being floated at the opposite face of the cloth-texture relative to such warp-threads, whereby the cloth-texture forms less longitudinal fulness of material at an elastic cord than in the band between two elastic cords, 60 with resulting throwing of the greater longitudinal fulness of the said band into transversely-extending gathers, and leno stitching threads, each of which zig-zags back and forth across the top of an elastic 65 cord and is caught at the opposite sides of the elastic cord alternately by weft-floats at the under face of the cloth-texture.

JAMES A. HENDLEY.
